UNITED STATES PATENT OFFICE.

JOHN W. HALE AND JOHN I. GALEY, OF GRAND PRAIRIE, TEXAS.

BOLL BREAKER AND CLEANER.

1,110,776.

Specification of Letters Patent. Patented Sept. 15, 1914.

Application filed May 8, 1914. Serial No. 837,188.

To all whom it may concern:

Be it known that we, JOHN W. HALE and JOHN I. GALEY, citizens of the United States, residing at Grand Prairie, in the county of Dallas and State of Texas, have invented a new and useful Boll Breaker and Cleaner; and we do hereby declare the following to be a full, clear, and exact description of the invention, such as will enable others skilled in the art to which it appertains to make and use the same.

This invention relates to a new and useful boll breaker and cleaner, and an object of the invention is to provide a device of this character, involving essential and practical features of construction.

One of the features of construction is the provision of a casing having a pair of revolvable cylinders provided with boll breaking arms, adapted to intermesh with additional boll breaking arms projecting from rockable shafts mounted in the lower portion of the casing. As the cylinders revolve the boll breaking arms act to break the boll cotton as it is forced through the casing by a current of air.

Another feature of the invention is the provision of means for simultaneously rocking said rocking shafts, to adjust the boll breaking arms of said shafts in different positions, said means including means to hold the rockable shafts adjusted.

Another feature of the invention is the provision of a downwardly extending trash box extending from the casing, there being screening means between the trash box and the casing, bridging between the cylinders but offset below therefrom, and through which the trash passes. In other words, the screening means separates the trash and motes, the trash and motes passing into the box, whereas the cotton bolls pass on through the casing to its outlet.

Another feature of the invention is the provision of a removable hood, which may be removed, in order to remove the cylinders for repairs and cleaning.

In practical fields the details of construction may be subjected to alterations, falling within the scope of what is claimed.

The invention comprises further features and combination of parts, as hereinafter set forth, shown in the drawings and claimed.

In the drawings:—Figure 1 is a view in side elevation, showing the improved cotton boll breaking machine constructed in accord-

ance with the invention. Fig. 2 is a view in elevation showing the opposite side. Fig. 3 is a longitudinal sectional view showing parts in elevation, other parts in section, and illustrating the boll breaking arms of the rocking shafts adjusted in different positions in dotted lines. Fig. 4 is a transverse sectional view. Fig. 5 is an enlarged detail view of a portion of one of the cylinders, illustrating the construction thereof and showing one of the boll breaking arms connected thereto. Fig. 6 is a sectional detail.

Referring to the drawings, 1 designates a casing having an inlet end 2 provided with a passage 3, and a discharge end 4 provided with a discharge passage 5, and through which casing and said passages cotton bolls are forced by a current of air. The side and the top of the casing are cut away, to receive a hood 6 corresponding in shape to the cutaway portion 7 to fit the same. The sides of the casing adjacent the lower edges of said cutaway portion are provided with metal bars 8, bolted in place as at 9. Said bars 8 are provided with bearings 10, in which the shafts 11, 12 and 13 are mounted, and when the hood 6 is in place as shown in the drawings the bearings 14 of the sides of the hood coöperate with the bearings 10 of the bar 8, to hold the shafts in place. The bearings 14 are formed in a bar 15, which is bolted to the bar 8, and is also carried by the hood. The hood is fastened in place as shown at 16 by suitable bolts or screws. Upon one end of each of said shafts 11 and 13 is a pulley 18, and mounted on one end of the shaft 12 (which is an idle shaft, in so far as rotating any member on the interior of the casing, is concerned) is a pulley 19. Passing over one of the pulleys 18 and under the pulley 19, then over the other pulley 18 is a suitable belt 20, adapted to be driven by any suitable means (not shown), for imparting motion to the pulleys and said shaft. The purpose of providing the idle pulley 19 is to insure greater belting surface between the belt and said pulleys 18, as shown in the drawings. Bearings 14 of the hood have tubes 21 connected thereto as at 22, said tubes are provided with suitable oil cups 23, in order to keep the bearings well lubricated. Keyed at 24 upon said shafts 11 and 13 are cylinders 25 and 26. The cylinders are provided with spokes, hubs and rims 27, 28 and 29. The rims 29 are constructed with depressions 30 in between said spokes.

95

100

105

110

A sheet metal casing 31 having longitudinal depressions 32 engage about the rims of each cylinder, the longitudinal depressions of each sheet metal casing fitting in the depressions of said rims. A metal band surrounds each end of the sheet metal casing to hold the same to said rims, there being rivets for holding the bands and the sheet metal casing and the rims together, said rivets and bands are designated by the numerals 33 and 34. The cylinders are provided with cotton boll breaking arms 35 and 36, which are curved as shown and in the form of blades. These arms are provided with tapering portions 37 and reduced extensions 38 having exterior threads 39. The tapering portions and the reduced parts 37 and 38 pass through the bands and the bars 39, there being spring washers 40 and nuts 41 for holding said arms in place, said spring washers are interposed between the nuts and said bars 39. The bars 39 connect the bands of each cylinder, as shown in the drawing, and are arranged adjacent the longitudinal depressions 32 of the casing 31. The portions of the bars between the bands constitute means to receive the reduced parts and tapering portions of other arms, as shown. Bolted to the sides of the casing are plates 42 having bearings 43, in which the pintles 44 of the shafts 45 and 46 are mounted. The portions of said shafts between the sides of the casing are square or rectangular in cross section, in the present instance, but they may be any suitable shape. Arms 47 and 48 are provided. These arms 47 and 48 have tapering and reduced parts 49 and 50, passing through the shafts 45 and 46, there being nuts and spring washers 51 and 52 for holding said arms 47 and 48 to said shafts or rods 45 and 46.

In Fig. 1 it will be observed there is provided four rocker arms 52, 53, 54 and 55, one being carried by one end of each of said shafts or rods 45 and 46. The arms 52 and 53 are connected by a link 56, and the arms 54 and 55 are connected by another link 57. Pivoted at 58 to the bar 8 is an operating lever 59, and pivotally connected at 60 to said lever are connecting bars or links 61 and 62. The link 61 is connected to the arm 53, whereas the link 62 is connected to the arm 54. A segment rack 63 is secured at 64 to one side of the casing, and the lever 59 is provided with a dog 65 to engage any one of the teeth of the rack, to hold the lever 59 in adjusted positions, there being a hand grip 66 having a rod connection 67 with the dog for operating the same. When the lever 59 is operated in one direction or the other, the arms 47 and 48 may be disposed in different positions, as shown in full and dotted lines in the drawings. Cotton bolls upon first being passed through the machine to be broken, the arms 47 and 48 are adjusted as

shown in full lines, and upon passing the cotton bolls through the machine a second and third or fourth time, said arms 47 and 48 may be adjusted in any one of the dotted positions. A section 68 of the casing adjacent the shafts or rods 45 and 46 may be removed, to have access to the arms 47 and 48. Projecting downwardly from the casing is a trash box 69 having closure members or doors 70 hinged at 71, whereby the trash and motes may be removed. Interposed between the trash box and the interior of the casing is a screening member 72, which may be constructed of meshwork or the like, or may be constructed of perforated sheet metal. The screening member 72 is designed for separating the trash and motes from the cotton bolls as they are broken, by the intermeshing and beating of the arms 35 and 36 and 47 and 48. Carried by the interior face of the hood is a pair of concaved deflecting shields or plates 74 and 75, merging to an apex as shown at 76, and constituting means for deflecting the air current or draft between said cylinders. However, the majority of the air draft or current passes below the cylinders, together with the cotton bolls, while the other portion of the air draft or current is deflected downwardly between the cylinders by either one of the deflecting plates 74 and 75, it depending upon which way the air draft and the boll are passed through the machine. The air current which is deflected downwardly between the cylinders acts to mix and stir the air which is passed below the cylinders, thereby generating what may be termed in the present instance as a whirlwind of air below and between the cylinders adjacent the screening means, thereby acting to thoroughly blow the trash and motes from the cotton bolls as they are broken.

The invention having been set forth, what is claimed as new and useful is:—

1. In a cotton boll breaking machine, a casing, a pair of cylinders mounted in bearings therein, one in each end of the casing, said cylinders having beating arms, a pair of shafts journaled adjacent and below each cylinder provided with beaters, means for rocking said shafts to adjust the beaters in different positions, screening means in the casing below and between the cylinders, and a refuse box below the screening means.

2. In a cotton boll breaking machine, a casing, a pair of cylindrical beaters, one journaled in each end of the casing, a pair of shafts journaled in the casing below and adjacent each cylindrical beater and provided with cotton beating arms, means for rocking said shafts simultaneously, for simultaneously adjusting the beating arms in different positions, screening means below and between the cylindrical beaters, and a trash box below the screening means.

3. In a cotton boll breaking machine, a casing, a pair of cylindrical beaters, one journaled in each end of the casing, a pair of shafts journaled in the casing below and adjacent each cylindrical beater and provided with cotton beating arms, means for rocking said shafts simultaneously, for simultaneously adjusting the beating arms in different positions, screening means below and between the cylindrical beaters, and a trash box below the screening means, and means for deflecting an air current downwardly and between said cylinders.

4. In a cotton boll breaking machine, a casing, a pair of cylindrical revoluble beaters, one journaled in each end of the casing, a pair of shafts mounted in each end of the casing below and adjacent each cylindrical beater and provided with beating arms adapted to intermesh with the arms of the cylindrical beaters, the shafts of each pair having link connections, both pairs of shafts having link connections, an operating lever connected to the second link connection, for manually rocking said shafts simultaneously for adjusting the beating arms in different positions, screening means below and between the cylindrical beaters, and a refuse box below the screening means.

5. In a cotton boll breaking machine, a

casing, a pair of cylindrical revoluble beaters, one journaled in each end of the casing, a pair of shafts mounted in each end of the casing below and adjacent each cylindrical beater and provided with beating arms adapted to intermesh with the arms of the cylindrical beaters, the shafts of each pair having link connections, both pairs of shafts having link connections, an operating lever connected to the second link connection, for manually rocking said shafts simultaneously for adjusting the beating arms in different positions, screening means below and between the cylindrical beaters, and a refuse box below the screening means.
